UNITED STATES PATENT OFFICE.

HUGH H. WHITEHEAD, OF PALMETTO, FLORIDA.

CRATE-MAKING MACHINE.

Application filed February 15, 1921. Serial No. 445,241.

To all whom it may concern:

Be it known that I, HUGH H. WHITEHEAD, a citizen of the United States, residing at Palmetto, in the county of Manatee and 5 State of Florida, have invented a new and useful Crate-Making Machine, of which the following is a specification.

This invention relates to box or crate forming machines, it being the primary object of the invention to provide means for 10 clamping the ends and partitions of a box or crate to support the same in upright positions so that the side members of the box or crate may be secured to the end sections 15 or partitions, with facility.

A further object of the invention is to provide a device of this character which may be controlled and operated by foot levers, thereby enabling the operator to have 20 unlimited use of his hands to accomplish the nailing operation.

A still further object of the invention is the provision of means for automatically locking the clamping members in their 25 clamping positions, thus eliminating the necessity of the operator manually locking the clamping elements.

With the foregoing and other objects in view which will appear as the description 30 proceeds, the invention resides in the combination and arrangement of parts and in the details of construction hereinafter described and claimed, it being understood that changes in the precise embodiment of the 35 invention herein disclosed, may be made within the scope of what is claimed, without departing from the spirit of the invention.

Referring to the drawings:

Figure 1 illustrates a plan view of the 40 machine.

Figure 2 illustrates a side elevational view of the same.

Figure 3 illustrates a front elevational view thereof.

Figure 4 illustrates a vertical sectional view through the machine.

Figure 5 illustrates a detail view of the clamping elements in their released position.

Figure 6 illustrates a front elevational 50 view of the same.

Figure 7 illustrates a plan view of the clamping elements in their clamping positions.

Figure 8 illustrates a front elevational 55 view of the same, and

Figure 9 illustrates the clamping elements in their clamping and locked positions.

Referring to the drawings in detail the machine includes a base including front and rear bars 5 and 6 respectively and side bars 7, to which are secured the uprights 8 and 9, and the angularly disposed brace bars 10 which have their lower ends connected to the side bars 7, the upper ends thereof being secured to the uprights 9 to brace the same 65 against rearward movement.

The bars 8 are connected adjacent the upper ends thereof as by means of the transversely extending beam 11, the beam 11 forming a table with the uprights 8 and 9 70 to support the box sections thereon.

As shown, the upper ends of the uprights 9 extend above the uprights 8, to form a stop for the table, and to these extensions, the horizontally disposed bars 12 are secured, which arms form the stationary jaws 75 of the clamping element, to be hereinafter more fully described.

Metallic plates 13 are secured to the table and have the rear portions thereof secured 80 to the upper extensions of the uprights 9, to reinforce the connection between the uprights 8 and 9 and eliminate wear on the wooden surface of the table. Disposed substantially intermediate the side edges of the frame of the machine, is a plate indicated 85 at 14, which plate has its rear end extending upwardly and inwardly as indicated at 15, which end is bifurcated as at 16 to receive a partitioning section of a crate to temporarily support the same in an upright position, pending the clamping thereof by the clamping elements of the machine.

An important feature of the invention lies in the construction of the clamping elements, 90 which include the relatively long pivoted arms 17 pivotally connected to the frame as at 18, the outer or free ends thereof being inturned as at 19 to provide a spring jaw 20, there being provided an adjusting screw 100 21 passing through one portion of each arm, and having its end contacting with the spring jaw 20, whereby movement of the adjusting screw 21 producing a relative movement of the spring jaw to cause the 105 same to move toward and away from the bar 12 associated therewith.

Operating between the arms 17 are the jaws 22 which are supported indirectly by the arms 17 as by means of the plates 23 110

- which have hinged connection with the jaws 22 as by means of the plates 24, the connection between the plates 23 and 24 being made by the hinges 25, there being provided 5 a hinged connection 26 between the jaws 22, which hinged connection 26 also provides means for connecting the operating rod 27 to the jaws 22 so that the jaws and arms may be operated simultaneously.
- 10 A foot lever 28 has one end connected to the rear of the frame, the forward end thereof extending beyond the plane of the front wall of the machine as at 29 to provide a foot contacting means, whereby the 15 rod 27 may be operated by movement of the lever 28.
- Connected to the foot lever 28 is a coiled spring 30 which has one extremity anchored to the frame to assist in moving the foot 20 lever 28 to its upper or unlocking position, when the foot lever has been released by the operator. It is to be understood however that the connection between the operating rod 27 and jaws is such as to move the plates 25 which connect the rod 27 and jaws 22 to a position below a direct horizontal line, whereby the jaws 22 are automatically locked and held into position with the sections clamped thereby.
- 20 Disposed under the foot lever 28 is a lever 31 which has an offset portion 32 contacting with the lower surface of the foot lever 28 so that movement of the lever 28 to its lower or locking position causes the lever 31 to 35 move to its upper position. It will thus be seen that when the lever 31 is in its upper position, movement of the lever to its lower position, or to a position as indicated by Figure 4 of the drawings, moves the foot lever 28 to its upper or unlocked position to release the sections of the box or crate clamped by the machine. Thus it will be 40 obvious that the lever 31 may be employed in place of the spring 30 should it be desired to move the arms gradually to their 45 unlocked positions.

In the modified form of the invention as illustrated by Figures 5 to 9 inclusive, a novel form of clamping jaw is shown, and

in these figures the central clamping jaws 50 have been omitted, the machine being especially designed for box making.

With reference to Figures 5 to 9 inclusive of the drawings, the arms 33 are substantially the same as the arms 17, the connection 55 between the arms being a pair of hingedly connected plates 34 and 35, which have connection with the operating rod 36 as at 37. In Figure 8 of the drawings, the arms are shown as in their clamping positions, and it 60 will be seen that when the arms 33 are further moved, as by the operation of the rod 36, the plates 35 take positions as illustrated by Figure 9, whereupon the plates 35 are moved below a direct horizontal line, with 65 the result that the arms 33 are locked into their clamping positions.

In the operation of the device, end sections as illustrated by Figure 2 of the drawings, and designated by the reference character 70 40, are positioned between the bars 12 and jaws 20, the central or partitioning section being disposed between the jaws 22. It is obvious that upon movement of the foot lever 28 to its lower position, the jaws are 75 brought into clamping relation with each other to clamp the sections in their upright positions, whereby the side boards of the box may be easily secured thereto.

Having thus described the invention, what is claimed as new is:—

A box forming machine including a frame, arms having pivotal connection with the frame and having jaws at their outer ends, jaws mounted between the arms, hinge 85 members for connecting the jaws mounted between the arms, and means having connection with the hinge members for moving the arms and jaws mounted between the arms 90 simultaneously.

In testimony that I claim the foregoing as my own, I have hereto affixed my signature in the presence of two witnesses.

HUGH H. WHITEHEAD.

Witnesses:

W. E. ORO,
GEO. T. BLAKELY.
